UNITED STATES PATENT OFFICE.

JOSEPH H. RUSBY, OF NUTLEY, NEW JERSEY.

ELECTRIC SWITCH.

1,228,052.

Specification of Letters Patent. Patented May 29, 1917.

Application filed May 22, 1913. Serial No. 769,199.

To all whom it may concern:

Be it known that I, JOSEPH H. RUSBY, a citizen of the United States, residing at Nutley, county of Essex, and State of New Jersey, have invented new and useful Improvements in Electric Switches, of which the following is a specification.

This invention relates particularly to that class of electric switches which are operated by push-buttons to snap the blades into positive engagement with the contact devices. The object of the invention is to secure several novel features over the present art necessary to the production of a high grade switch, as for instance universal adjustment and standard dimensions, high electrical efficiency, mechanical strength and smoothness of operation, long operating life, and low producing cost.

20 In the flush type of electric switch important advantages have been secured by the particular construction of standard over all dimensions, adapted to accommodate all standard supporting fittings including 25 cover plates, while possessing universal adjustment after securing to a supporting surface.

Universal adjustment requires three directions of movement viz: longitudinally, laterally of the switch, and to and from the supporting surface. This universal adjustment is secured by providing a basic body of non-absorptive, non-inflammable, mechanically strong material for the support of 35 the actuating mechanism, contacts, and supporting wall lugs which are movably mounted upon adjusting screws. This insulated support may be provided with an armoring shell which may be formed of a single piece 40 of sheet metal which may constitute a support for the adjusting screws if desired.

The novel features of the invention are more fully described in the following specification and claims and illustrated in the accompanying drawings in which:

Figure 1 represents a front elevation of a flush type of electric switch embodying this invention.

Fig. 2 is a vertical section along the line *t t* of the same.

Fig. 3 is a section along the line *u u* of the same.

Fig. 4 is a horizontal section along the line *v v* of the same.

55 Fig. 5 is a section along the line *w w* of the same.

Fig. 6 shows a side elevation of a make and break mechanism.

Fig. 7 is a perspective view of a wall supporting lug.

Fig. 8 is a perspective view of a latch device.

Fig. 9 is a front view of the blades.

Fig. 10 is a perspective view of a lug carrier piece.

Fig. 11 is a similar view of a contact device.

Figs. 12 and 13 are detail sections of modifications showing the adjustable lugs and block.

Fig. 13^a is a detail front view of Fig. 12 showing the cover removed.

Fig. 14 is a front elevation of a surface type of electric switch showing the cover removed.

Fig. 15 is a vertical section along the line *x x* of the same.

Fig. 16 is a horizontal section along the line *y y* of the same.

Fig. 17 is a similar section taken along the line *z z* of Fig. 14.

Fig. 18 is a rear view of an insulated support.

Fig. 19 is a front elevation of one of the insulated supports.

Fig. 20 is a detail side elevation of the blades.

Fig. 21 is a side elevation of a make and break mechanism the blades having been removed.

Fig. 22 is a detail view of a push button.

Fig. 23 is a perspective view of a modified form of carrier piece.

In these drawings the letter *a* designates an insulating supporting block preferably 95 formed of porcelain with an open rear portion *b* having dome shaped interior chambers *c* the purpose of which will be herein-after explained. An armoring shell *d* is fitted to the exterior of the block and by channelling the ends of the block and bending the sheet at *e* it will fit into the channels, this shell may be bent from one piece of sheet metal with minimum of waste and when slipped over the block will conform tightly 100 without springing away. The shell has projecting wings or lugs *f* which serve as supports for adjusting screws *g* each screw being located at the top and bottom of the block and housed in the channels of the 105 block. By having the shanks of the adjusting screws housed in the block it shortens the 110

total length of the block in the wall receptacle for longitudinal movement and the conductors. Mounted on each of these adjusting screws is a lug *h* and these lugs by their 5 particular form, provide distinct advantages over previous ones, where a switch possessing universal adjustment is desired. The lugs are bent forward from the main stock at *i* for coöperation with wall supporting 10 screws, and backward at *j* and *k* top and bottom respectively, these backward bends form strong mountings for the adjusting screw *g* and the top backward bend forming clearance for a cover securing support as 15 well as a wall securing support.

Where a cheaper form of adjustment is desired it can readily be provided by hinging a plain lug *m* upon a top strap by means of a post or inverted screw *n* as shown in 20 Figs. 12 and 13^a wherein the post forms a swivel hinge for mounting the lug on a strap *p* and the post may also serve as a mounting for a base closure plate *q* or the projection on the bottom of the switch for supporting 25 the screw of the post end, may be formed integral with the switch body, as for instance a lug of porcelain body block. Or the post or screw *g* need not be dependent upon even a top strap but may be formed with a projection 30 on the switch body top and another on the bottom place *q* for the screw support, the lug *h* is mounted on the screw and the screw top is tapped for a cover securing screw *r* as indicated in Fig. 13 or this lug mounting 35 may enter the lug from below as shown in Fig. 12, the lug hinging upon the upper screw or post end.

The make and break operating mechanism includes a pair of push buttons 25 having 40 shanks pivoted at 26 to a spring actuating lever piece 27 mounted on a pivot bolt 28. The said bolt is supported in a frame 29 the front portion of which is adapted to be fastened by means of a screw 30 to the upper 45 portion of the interior of the block. A lug piece 31 is mounted on the pivot bolt 28 and it has connected to it a set of blades 32. Hard fiber or mica 33 insulates the blades from the remainder of the mechanism. A 50 spring 34 is coiled about a drum 35, and this drum is mounted on a hollow spindle 39 fixed to the lever piece 27 noted above. A latch detent 36 is provided with a lug and it is pivoted at 37 to the support and this latch 55 is connected at 38 to the shank of one of the push buttons. The lug of the detent coacts with one or the other of the edges formed on the rim of the lug piece 31 mentioned above.

The lever piece 27 has a cross arm and the 60 blade carrier 31 has a similar arm extending between the shanks of the coiled spring. The lever piece 27 is operated by the push buttons and the carrier 31 actuates the blades to snap into or out of engagement with the 65 contact devices.

The contact devices consist of a series of plates 40 with binding screws 41 threaded through the plates. Posts 42 connect the plates to the insulated block and contact upper devices 43 and lower contacts 44 are 70 connected to the plates and posts respectively.

By supporting the working mechanism separatively upon the insulating body *a* and the closure base plate *q* upon the top strap 75 by the connecting posts *n* or adjusting screws *g* through insulating of mechanism is secured so that if the blade insulation breaks down, no grounding of current may occur thereby.

By designing the insulating block *a* in the form of an inverted receptacle, closed at top or face, upon the outside of which face the conductor contacts 40 are supported, and chambered out on under side for reception 85 of the working mechanism, the contacts connecting with the blades through closed apertures in the insulating block body and the lower chamber closed by closure plate *q*, the break arc is entirely confined inside the 90 switch.

By locating the common swing center pivot 28 low down in switch chamber, the conductor contacts 43 for one end of the blade will be above the blade end in the 95 chamber, and the conductor contacts 44 for the other end of the blade will be located below the blade end in lower part of the chamber. This arrangement of blades, contacts and binding screws, provides a very 100 high electrical efficiency. The blade end can be split as indicated in Fig. 9 and contact plain or vice versa.

By the method shown of forming and securing the conductor contacts 41 an advantage 105 is obtained; for by mounting the contact plate 40 upon a shouldered post 42 as for instance by riveting, a rigid right angle of contact and post may be secured with a thin rivet neck thus clearing the binding 110 screw head. By separating the contact slightly above insulating block surface, as for instance by forming a ridge on contact, post, or insulation about the post, and drawing the contact down to its place in a seat in 115 the insulating block, then securing means on lower end of post, as for instance a nut, seated into the insulating block, a true and rigid alinement of contact is secured. This method is not limited to the inverted block 120 form as shown, but is as applicable to switches of open top form.

The conductor contacts 40 may be formed of heavier metal to provide current capacity and stock for ample binding screw 125 threads, while the blade contact portions 43 and 44 may be formed of thinner metal of high conductivity such as hard drawn copper and secured upon the main contact as shown, thus obviating the need of springing the 130

blades open widely which excessively wide springing tends to shorten the life of the blade by breaking, or of providing room for a thick contact piece in the blade chamber.

5 By hanging the working supporting frame 29 from the insulating block *a* at the top of the chamber and seating at 29' in grooves at the bottom of the insulating block, see Fig. 2, perfect and rigid alinement and support is obtained.

10 The top securing screw 30 for this supporting frame may be locked as indicated in Fig. 4, after screwing home, by setting an edge of the head into the corresponding seat 15 in the insulating block *a* under the screw head.

15 By employing the main swing center pivot 28 as a supporting means for the blade, and locating the other needed blade fastening 20 devices above this center, the field is cleared below the center, and no space is required there which would add depth to the switch. This form of blade 32 can be punched out from the sheet a single way of the grain 25 providing strength to bent portions.

20 By locating the latch 36 as far to one side of the switch as practically expedient and shouldering down the spring drum 35 and hollow spindle 39 to small diameter immediately under the latch, ample swing room is 30 secured for the latch, and then, by increasing the diameter of the spring supporting drum aside of the latch swing space, room is provided for a spring 34 of very much 35 larger diameter and size than any hitherto secured.

30 By constructing the spring drum 35 of drawn sheet and mounting upon the hollow spindle 39 which spindle also carries the lever piece 27 a simplification is effected and a reduction of metal weight, also a ready means of confining the operating spring by turning back a lug upon the wall of the drum. As indicated in Fig. 17 the pivot 40 bolt 28 has pointed ends bearing against the porcelain sides of the insulated block preventing longitudinal play of the pivot and designed to form a pivot point with an insignificant degree of friction on the point.

45 By forming the push button shanks with divided ends 45 as shown in Fig. 22 a double support is formed for the rivet pin 26 thus saving switch depth space and adding strength.

50 A compact form of this switch is shown in the surface type modifications wherein a push button switch is provided, adapted to be merely secured upon a wall surface as the present rotary surface snap switch is secured 55 though this type may be adjustably mounted into wall receptacles. As shown in Fig. 17 the means for adjusting the switch consists of screws 46 coöperating with a slot 47 formed into the insulated block *a*. The adjusting screw 46 has an angular head with a

tapped portion arranged in the slot and a shoulder to bear against the rear portion of the block, a screw 48 is adapted to clamp the screw 46 to the block. By adjusting the screw 43 the switch may be turned around or rotated on the screw heads within the limits of the slots to line the push buttons.

50 By extending the insulating base *a* of the switch through the bottom of the armoring shell as shown at 49 and seating the switch 75 upon this insulating base, a space for air insulation is provided between armoring shell and wall post, in case the blade insulation breaks down and also prevents shifting of the insulating base *a* in the shell.

80 By turning in the lugs 51 on the armoring shell top upon the seats in the insulating base, this base is securely clamped into shell, regardless of any additional securing means.

85 By extending the ends of the flexible shell lining insulation under these turned-in lugs before the lugs are turned, the lugs also secure the flexible insulation 50 into place.

80 The turning in of these lugs on armoring shell *d* also provides seats for truing lugs on 90 a cover plate 52, preventing any shifting of cover plate which might bind the push buttons 25 and prevent freedom of action.

95 The sheet insulation 50 provides separation of the contact piece from the shell.

90 The frame lugs 29 as indicated in Fig. 17 for inclosing the push buttons, prevent the swing of the metal button shanks over against the live metal parts such as contacts.

100 The riveting of flexible spring contacts 43 as shown in Fig. 16 upon the conductor contacts 40 economizes space and provides electrical conductivity.

105 By forming the blade carrier in two parts as shown in Fig. 23, great strength and rigidity are obtained, while the latching lug 31 is braced to great mechanical stiffness.

110 By bending in the ends of this lug 31 of the blade carrier, they can be formed to clear the blade by ample insulating space, and at the same time form stops against the shell bottom.

115 By shouldering the inside pivot 28 upon which these blade carriers 31 and 39 are mounted, with double riveting shoulders, the carrier can be riveted upon the first one and the remaining one may form a securing rivet support for the blade, thereby serving as a preventive of longitudinal play as noted previously.

120 The elongated screw slots 47 in the insulating body *a* allows rotary adjustment of switch for correct alinement.

I claim:

125 1. An electric switch comprising an insulating supporting block, an adjusting screw and a wall supporting lug, said lug formed of a main stock, extending parallel with said adjusting screw, a portion bent forward from said main stock, said forward 130

- extending portion slotted to receive wall securing means, a portion having a threaded hole and bent backward from the base of said main stock, and a second portion having a threaded hole and bent backward from said main stock, above said first backwardly bent portion, said adjusting screw threaded through said threaded holes for adjustably mounting said lug upon said adjusting screw.
2. An electric switch comprising an insulating supporting block, an adjusting screw, and a supporting lug, said lug adjustably hinged upon said adjusting screw and having a main body extending parallel with said adjusting screw, said main body curved laterally away from said adjusting screw to provide swing room.
3. An electric switch comprising an insulating supporting block, a wall securing means, conductor contacts, and an operating mechanism, said mechanism including a base, a supporting stud on the base, an operating lever piece movably mounted on the stud, and a tubular member carried by the lever piece for mounting a spring.
4. An electric switch comprising an insulating supporting block, an overhanging projection on the face of said block, said projection having a hole for a cover securing device, a post supported on said switch, a switch supporting lug swingingly mounted on said post, said lug being slotted to coact with a wall securing device and to provide clearance for said cover securing device.
5. An electric switch comprising an insulating supporting block, a strap on the face of said block, a base plate on the back of said block, connecting posts for mounting said strap and back plate upon said block and an adjustable supporting lug hinged upon said strap by said connecting post.
6. An electric switch comprising an insulating supporting block, a strap on the face of said block having an overhanging end, an adjusting screw extending through said strap, an adjustable wall lug threaded upon the adjusting screw, a tapped hole in the overhanging end of strap for cover securing means; the said adjustable lug slotted to clear said cover securing means and said overhanging strap end and to receive wall securing means.
7. An electric switch comprising an insulating supporting block, a strap on the face of said block having an overhanging end, a supporting post extending from said strap, an adjustable wall lug hinged upon said post, a tapped hole in the overhanging strap end, for cover securing means, the said adjustable lug slotted to clear said cover securing means and to receive wall securing means.
8. An electric switch comprising an insulating supporting block having an adjusting screw and a switch supporting lug, said lug having a plurality of supports for co-operation with said screw.
9. An electric switch comprising a supporting block, an overhanging strap on the face of said block, an adjusting screw extending through said strap, an adjusting lug threaded upon said screw, a hole in the overhanging end of strap for the cover securing means, the said adjusting lug slotted to clear said overhanging strap, and to receive support securing means.
10. An electric switch comprising a supporting block, said block end channeled from face toward back, a projection on the face of said block and another projection on the back of said block, said projections overhanging said channel, an adjusting screw rotatably supported between said projections and extending in said channel longitudinally thereof, and a supporting lug adjustably supported upon said screw.
11. An electric switch comprising an insulating supporting block having a chamber, a contact blade in said chamber, said blade being formed of a central stem portion for securing the said blade upon a mounting support, branching contact arms extending from opposite sides of the central stem, contacts in said chamber located above and below the blade contact arm.
12. An electric switch comprising an insulating supporting block having a wall and a chamber adjacent the wall, a conductor contact seated on the face of the block on the wall, and conductor means extended from the contact through the wall into the chamber.
13. An electric switch comprising an insulating supporting block having a seat on its face and a hole extending from said seat toward the back of said block, a post in said hole, a conductor contact mounted upon said post and seated in said seat, and a device at back of said block for securing said post.
14. An electric switch comprising an insulating supporting block having a hole extending vertically through the block, and provided with a recess at the upper end of the hole, a post arranged in the hole, a contact located in the recess and secured to the post, and a device at the lower end of the post for retaining the contact in the recess.
15. An electric switch comprising an insulating supporting block having a domed chamber located in the block with an insulating wall forming the top of the chamber, said wall having a depression, a contact device arranged on the wall, a binding screw threaded to engage the contact and project into the depression.
16. An electric switch comprising an insulating supporting block having a chamber, a contact blade in said chamber, a con-

tact in said chamber above one end of said blade and a contact in said chamber below the opposite end of said blade.

17. An electric switch comprising an insulating supporting block, a chamber in said block, and conductor contacts in said chamber said conductor contacts being the only permanently fixed conductors in said chamber.

18. An electric switch comprising an insulating supporting block, said block having

a countersunk hole, a seat in said countersink, a screw in said hole and the screw head adapted to be set into said seat to prevent turning.

In testimony whereof I have hereunto set my hand in the presence of two subscribing witnesses.
